UNITED STATES PATENT OFFICE

RICHARD J. HOLZHAUSEN, OF WESTPORT, CONNECTICUT, ASSIGNOR TO THE COMPO
MANUFACTURING COMPANY, OF WESTPORT, CONNECTICUT, A CORPORATION OF
NEW YORK.

STAPLING MACHINE.

Application filed December 14, 1921. Serial No. 522,220.

To all whom it may concern:

Be it known that I, RICHARD J. HOLZHAUSEN, a citizen of the United States, residing in the town of Westport, county of Fairfield, State of Connecticut, have invented certain new and useful Improvements in Stapling Machines, of which the following is a specification, reference being had to the accompanying drawings, illustrative of 10 one particular embodiment of my invention.

This invention relates to improvements in stapling machines, and in particular appertains to such machines in which a pre-formed strip of staples is automatically fed under a plunger so that the proper operation of the plunger severs a single staple from the strip and places and clinches the same. While stapling machines of this general type are known, the particular embodiments to which this application applies involves constructions which will insure the proper positioning of each individual staple, and in case the individual staple ready for 25 use has its prongs bent, the machine will straighten the prongs, and in any event will prevent the bending of the prongs in the operation of severing the individual prong from the strip. Furthermore, the use of 30 these improvements assures the straightening of bent prongs, or the prevention against bending, so that in the actuation of the machine the prong will be properly directed 35 for its journey into the clinched position, thereby insuring perfection of actuation of the machine and the avoidance of clogging of the machine, which latter has been a great difficulty in stapling machines heretofore used. These and other advantages, as 40 will hereinafter appear, are accomplished automatically by the relation and co-action of parts which will be hereinafter described in connection with particular embodiments 45 of my invention shown in the accompanying drawings, in which:

Fig. 1 is a side elevation of a stapling machine with the hand-piece and upper end of the plunger in section.

Fig. 2 is a vertical section through the axis of the plunger and the immediately associated parts of the machine.

Fig. 3 is a similar section on the axis of the plunger when the plunger is depressed 55 in the clinching position.

Fig. 4 is a section on the vertical axis of the plunger at right angles to the section shown in Fig. 3.

Fig. 5 is a vertical section on the axis of the plunger similar to Fig. 4, but double the 60 scale and with slight modifications.

Fig. 6 is a horizontal section at the lower end of the plunger and immediately associated parts on the line 6—6, Fig. 5.

Fig. 7 is a horizontal section at the lower end of the plunger, and immediately surrounding parts on the line 7—7 of Fig. 5.

Fig. 8 is a perspective view of a portion of the plunger with the staple prong 70 straightening plate attached and the straightening plate releasing or tripping stop shown in relative position.

In the particular embodiment here shown, the base 1 is supported on feet 2 with the usual staple anvil 3 forming an integral 75 part of the base, while two legs 4, integral with the base, carry pivots for the guide track 5 secured in the body 6, in a manner permitting the pre-formed strip 9 to ride along the track 5 to a position above the channel 10 where the end staple may pass down after severance from the strip, to the anvil 3 where it is clinched as shown in position 9^a in Figs. 4 and 5.

The plunger 12 is guided between the inwardly facing walls formed at the end of the body 6, the outwardly projecting ridge on the plunger closely fitting the adjacent portion of the walls, while the lateral flanges 12^a—12^b on the plunger have the sides of the guide plate 13 on their outer surface, and thus with the guide these lateral flanges engage recesses in the walls in the end of the body 6, forming channels whereby the 90 plunger and guide plate reciprocate in the manner hereinafter more fully described.

The plunger 12 has the cushion-head or hand-piece 14 and a spring 15 resting under the cushion-head and on top of the body 6, 100 tends to normally raise the head 14 and thereby the plunger into the position shown in Figs. 1 and 2. The plunger also has the cam 16 engaging the feed operating plunger 17 to actuate the same in the usual manner 105 so that a depression of the plunger sets the feed mechanism, which upon the retraction of the plunger moves the pre-formed staple strip one step in advance to position the end staple above the guide channel 10.

110

The straightener or straightening guide 13 comprises the straightening flanges 18—18, which, as shown in Fig. 2, normally protrude below the longer end of the plunger 12, and as shown in Fig. 6 these flanges embrace or engage the back edge of the prongs of the foremost staple when the plunger starts downward on its journey. The upper end of the guide 13^a engages the recess 19 in the sides of the plunger so that the plunger will force the guide 13 and its straightening flanges 18 downward during the first fractional part of the journey of the plunger, and thereby force the flanges 18 between the legs of the first or foremost staple and the second staple on the end of the strip, assuring the straightened condition, or in case of a bent condition, forcing the straightening of the prongs of the foremost staple so that they are axially parallel with the movement of direction of the plunger, and thereby directed in the proper position for their journey through the balance of the guide channels and to clinching position, as illustrated at 9^a, Figs. 4 and 5.

In order that the straightening guide 13 and its straightening flanges 18 shall not puncture the paper which is being stapled, and if desired shall not even engage the paper, there is provided a trip release consisting of the plate 20 provided with an ear 21, having curved edges engaging the ears 22 laterally projecting from the upper ends 13^a of the guide 13, so that the engagement of these ears 22 with the tripping cam or flange 21 releases the upper ends 13^a from the recesses 19—19 in the sides of the plunger, thereby permitting the plunger to continue on its downward journey to effect the stapling, without carrying the guide 13 any farther than the point at which it is released by the tripping cam 21. The bridge 13^b holds the two sides of the guides 13 in spaced relation, thereby forming a unit grid of the guide and straightening flanges and releasing engaging means at the upper end, which is adapted to function automatically during the operation of the stapling machine when the plunger is driven down to perform its work.

The cam 16 on the plunger is tapered on the lower side and squared, or has an abrupt upper face adapted to engage the pin 23, which is a removable pin passing through holes from side to side near the upper front corner of the body 6, which thereby forms a stop for the upward movement of the plunger when it is pressed upward by the spring 15, and holds the plunger assembled with the body for ordinary use. This pin 23 can be readily removed to permit the upward withdrawal of the plunger and with it the guiding grid or frame 13, so soon as plate 20 is removed, by removing the screw 20^a, and, conversely,

the several parts are finished and may be assembled by inserting the grid and guide frame 13 on to the side of the plunger 12, which is then inserted between the walls of the casing 6 above the channels 10—10 after which the assembled parts are secured in position by attaching the plate 20 by the screw 20^a, and then inserting the pin 23 which prevents the removal of the plunger by the cam 16 engaging with the pin 23. 75

For the purpose of straightening the end staple, or for holding it straight or severed from the strip 9, the straightening flanges 18—18 project necessarily only to the extent shown in Fig. 5, at which point the guide plate 13 is released by the cam 21 tripping the ears 22—22, so that the remaining trip of the staple is through the channel 24 forming the lower part of the channel 10 and constituting a close confining guide for the journey of the staple beyond the ends of the straightening flanges. The channel 10 is for this purpose larger, as shown in Fig. 5, from the top to a point near the bottom to accommodate the sides of the guide plate 13, 90 and is restricted at 24, thereby forming a recess which furthermore limits the movement of the guide plate 13 after its upper end has been released by the tripping cam 21.

In either form the return upward movement of the plunger 12 carries the guide 13 until the lower ends of the straightening flanges 18—18 are above the normal position of the pre-formed staple strip as shown in Fig. 2, thereby permitting the horizontal or lateral feed of the staple strip by the usual automatic means in order to position the end staple in readiness for the next operation. The frictional engagement between the sides 12^a—12^a of the plunger and the straightening guide 13 causes the guide to be moved upward on the retraction of the plunger until the upward movement is arrested by the engagement of the bridge 13^b with the trip or stop 25, which is shown as a tang protruding from the wall 21 of the plate 20. This stop limiting the upward movement of the plate 13, permits the plunger 12 to pass upward until the notches 19—19 in the sides 12^a—12^a of the plunger 115 register with the upper ends 13^a—13^a, and by reason of the spring in these ends 13^a—13^a tending to bring these upper ends together, they snap into the depressions 19—19 and are thus brought automatically 120 in position to effect a positive engagement with the plunger for its next downward stroke, which forces the straightening flanges 18—18 positively into their functioning position to a sufficient extent to back up the 125 inner sides of the staple legs at the time the plunger severs them, as a preliminary to the driving and clinching action.

It will thus be seen that this stapler or stapling device, or as it is sometimes called 130

a binder, combines in a simple mechanism the various cooperating parts whereby a single stroke on the hand-plate drives the plunger which severs a staple from a pre-formed staple strip, and with the further movement as a result of the single stroke, drives the staple through the paper or other sheets and clinches the same, and at the same time assures the straightening of the staple prior to and during the severing of the individual staple from the strip, and after the operation of clinching the parts automatically return to their initial position with an automatic feeding of the staple strip for repetition of the stapling action immediately thereafter. The guide flanges 18 essentially back up the inner side of each of the two staple prongs in order to assure the prongs being directly properly downward in the direction for perforating of the sheet and the clinching. These straightening flanges also retract on the upward movement so as not to interfere with the immediately following automatic feed of the staple strip, and, nevertheless, the cooperation of the parts assures on the successive operation the proper engagement of the guide flanges, or at least the proper positioning of the guide flanges, for the purpose of preventing any tilting of the staple legs at the time of the severing operation, and in addition the straightening flanges will force any bent legs of a staple into proper functioning position preliminary to the moment of contact of the shearing end of the plunger with the top surface of the staple. By the positive engagement of the upper ends of the frame which carries the straightening flanges at its lower end, the downward action is positive to the extent necessary to straighten any bent staple, and whether the straightening flanges move farther than the initial position of the staple may vary in different machines, and the remaining journey of the staple after the severing act, can be through the usual side channels or may be between one usual channel wall and the inner wall of the straightening flanges, although after severing the staple is loose and requires no frictional hold for the remainder of its journey during the setting and clinching steps of the operation.

It is of importance, however, that having a positive movement of the straightening flanges to a sufficient extent to force the straightening of bent staples, the straightening flange must thereafter be freed from movement so as not to interfere with the functions of the plunger in severing and clinching, and, furthermore, automatic means is necessary to return the straightening parts to their initially functioning position. In the form herewith specifically described and illustrated, the cam trip mechanism is automatic and effective, and

the precise dimensions of the sliding frame and the plunger, and in fact the general arrangement and dimensions of any equivalent part performing the straightening action, may be varied without departing from this invention so long as it effects any of the novel results herein particularly set forth.

While variations may be made from the particular form herein shown and specifically described, without departing from the spirit of this invention—what I claim and desire to secure by Letters Patent is:

1. A stapling device comprising a plunger, staple straightening means adjacent said plunger and traveling throughout part 80 of its journey with the plunger and means for interrupting the movement of said straightening means before the plunger completes its journey.

2. In a strip staple machine, the combination with means for feeding a staple strip and means for severing and driving the individual staples of a member having means for engaging the foremost staple of said strip and holding the same against turning, and means for automatically stopping the movement of the engaging means after the severing of the foremost staple and before the driving means has completed its operation.

3. In a strip staple machine, the combination with means for feeding a staple strip and means for severing and driving the individual staples, a member having means for engaging the foremost staple on said strip and holding the same against turning, said member being guided for rectilinear movement transverse to the line of movement of the staple strip to carry said engaging means into and out of position so as to engage said staple, and means for stopping the movement of said member in conjunction with the actuation of the driving means and before the driving means has completed its operation.

4. A combination binder comprising a plunger and staple securing means, means for feeding a strip of pre-formed staples transversely to the direction of movement of the plunger, a guideway for the plunger the latter having a cutting and driving end, a slide having parallel portions at opposite sides of the plunger for straightening the prongs of any bent staples prior to the cutting action of the plunger, and means co-acting with the slide to arrest the movement of the slide upon a predetermined movement of the plunger.

5. In a stapling machine of the type described, a staple severing and a staple driving plunger, a slide co-acting with the plunger, faces on said slide to project behind the prongs of each staple during the initial movement of the plunger and means to arrest the movement of the slide after a pre-determined movement of the plunger.

terminated journey of the plunger and after the severing of the staple and before the plunger has completed its driving operation.

6. A stapling machine having a plunger 5 for severing staples from a strip and driving said staples through an outlet or channel, in combination with means associated with the plunger for straightening the prongs of each staple preliminary to severing the same and a trip to interrupt the movement of said straightening means and release it from the effect of the action of the plunger.

7. A stapling machine of the class described, having a pre-formed staple strip 15 and means to feed the same, a severing member and a plunger to drive individual staples after severing a straightening member normally out of the path of the staple strip and 20 means co-acting with the severing member whereby the straightening member is interposed between the prongs of the end staple and the prongs of the next staple in advance of the severing operation, and means for interrupting the movement of the straightening member during the further operation of the driving member.

8. A stapling machine of the class described, having a pre-formed staple strip 30 and means to feed the same, a severing member and a plunger to drive individual staples after severing, a straightening member normally out of the path of the staple strip and means co-acting with the severing member 35 whereby the straightening member is interposed between the prongs of the end staple and the prongs of the next staple in advance of the severing operation, means for limiting the movement of the straighten-

ing member after the severing operation and 40 means for resetting the straightening member to its initial position.

9. In a stapling machine of the character described, a plunger and a straightening guide co-acting with said plunger, means for 45 releasing the guide from the movement of the plunger and a stop for limiting the reTRACTING movement of the guide and a separate stop for limiting the retracting movement of the plunger. 50

10. In a stapling machine of the character described, a plunger, a straightening guide co-acting with the plunger, the plunger and the straightening guide being provided with devices whereby the plunger and the guide 55 have positive engagement during a portion of the working movement of the plunger, and means for effecting disengagement of the guide from the plunger at a point in the working movement of the plunger. 60

11. In a stapling machine of the character described, a plunger, a straightening guide co-acting with the plunger, the plunger being provided with notches in its sides and the straightening guide being provided 65 with spring ends to engage such notches and means co-operating with said spring ends in the movement of the plunger and guide to disengage the spring ends from said notches. 70

In testimony whereof, I have signed my name to this application, in the presence of two subscribing witnesses, this 9th day of December, 1921.

RICHARD J. HOLZHAUSEN.
